UNITED STATES PATENT OFFICE

91,202

DESIGN FOR AN ELECTRODE HOUSING

Leroy F. Hobert, Sandusky, Ohio, assignor to
The Universal Clay Products Company, San-
dusky, Ohio, a corporation of Ohio

Application September 23, 1933. Serial No. 49,327

Term of patent 3½ years

To all whom it may concern:

Be it known that I, LEROY F. HOBERT, a citizen
of the United States, residing at Sandusky, in the
county of Erie and State of Ohio, have invented
a new, original, and ornamental Design for an
Electrode Housing, of which the following is a
specification, reference being had to the accom-
panying drawing, forming part thereof.

The figure is a view in perspective of an elec-
trode housing embodying my design.

I claim:—

The ornamental design for an electrode hous-
ing, as shown.

In testimony whereof I have affixed my sig-
nature.

LEROY F. HOBERT.
